UNITED STATES PATENT OFFICE.

GEORGE R. BAILEY, OF BROOKLYN, NEW YORK, ASSIGNOR TO STERLING CASKET HARDWARE COMPANY, OF BROOKLYN, NEW YORK, A CORPORATION OF NEW YORK.

DESIGN FOR A CASKET-HANDLE AND LUGS.

50,599.

Specification for Design.

Patented Apr. 17, 1917.

Application filed March 7, 1917. Serial No. 153,197. Term of patent 7 years.

To all whom it may concern:

Be it known that I, GEORGE R. BAILEY, a citizen of the United States, residing at No. 502 Bedford avenue, in the borough of Brooklyn, county of Kings, and State of New York, have invented a new, original, and ornamental Design for a Casket-Handle and Lugs, of which the following is a specification, reference being had to the accompanying drawing, forming part thereof.

The figure is a plan view of a casket handle and lugs showing my new design.

I claim:

The ornamental design for a casket handle and lugs, as shown.

GEORGE R. BAILEY.

Witnesses:

A. M. VIKBERG,
VICTOR C. CONNIER.
